REINFORCED CARTON

Reynolds Guyer, St. Paul, Minn., assignor to Waldorf Paper Products Company, St. Paul, Minn., a corporation of Minnesota

Application June 19, 1946, Serial No. 677,861

1 Claim. (Cl. 229—16)

1

My invention relates to an improvement in reinforced cartons wherein it is desired to provide a carton possessing unusual resistance to compression.

Cartons of paperboard are often used to contain products which are relatively heavy. When such cartons are stacked one upon the other, they must be formed of paperboard of substantial thickness in order to possess sufficient stacking strength. The formation of certain cartons of heavy paperboard often is disadvantageous. Cartons of light stock may usually be sealed more effectively than cartons formed of heavier stock because of the fact that the carton of thinner stock will fold more readily and will fill up irregularities in underlying laminations. Heavier carton board will not easily flex to fill up a crack or seam and therefore leakage is more likely to occur. Furthermore ordinary glued end cartons usually have several thicknesses of carton stock at each end and only one thickness of stock throughout most of the carton walls. The increase in thickness of the carton stock adds thickness not only to the walls, but also to the sealing flaps where such thickness is not required.

It is the object of the present invention to provide a carton of the glued end type having two opposed walls thereof reinforced by forming these walls of double thickness. As a result a considerable degree of stacking strength is added to the carton without adding thickness to the paper board of which the carton is formed. As a result an effective seal may be provided and a minimum amount of carton stock is employed.

A feature of the present invention resides in providing a tubular carton in which the ends of the carton blank are overlapped to form a wall of double thickness, and in which the wall opposite the double thickness wall is provided with an auxiliary panel of paperboard adhered thereto. With such a construction two opposed walls of the carton are of double thickness while the remaining areas of the carton are of single thickness.

A feature of the present invention lies in the provision of a carton having a pair of reinforced opposed walls and having sealing flaps issuing from the ends of these walls which may be readily sealed in superimposed relation to form a tight carton. The side walls of the carton are possessed of unusual stacking strength while at the same time the superimposed sealing flaps are of sufficiently light stock to provide an effective seal.

These and other objects and novel features of my invention will be more clearly and fully set forth in the following specification and claim.

2

In the drawings forming a part of my specification:

Figure 1 is a perspective view of a carton showing my new construction.

5 Figure 2 is a transverse section through the carton between the upper and lower ends thereof.

Figure 3 is a diagrammatic view of the blank in readiness for the sealing operation.

10 Figure 4 is a plan view of the reinforcing panel used in conjunction with the main blank of the carton.

Figure 5 illustrates a carton blank similar to that shown in Figure 3 having a slightly different type of reinforcing panel used in conjunction therewith.

15 Figure 6 is a vertical section through the side walls, top and bottom of the carton shown in Figure 5.

The carton A, is in appearance, identical to 20 a sealed end carton of a common type. The blank from which the carton A is formed is best illustrated in Figure 3 of the drawings. The carton A includes a side wall panel 10, a rear wall panel 11, a side wall panel 12, and a front wall panel 13 connected together along parallel fold lines 14, 15, and 16. A reinforced panel 17 is connected to the panel 13 along the fold line 19 parallel to the previously described fold lines. The panel 17 in assembled form is designed to underlie the side wall panel 10 and to be secured firmly thereto.

25 A pair of fold lines 20 and 21 intersect the fold lines 14, 15, and 16 at substantially right angles thereto to form top and bottom edges for the side wall panels described. Top closing flaps 22 and 23 are connected to the panels 10 and 12, respectively, along the fold line 20 and are designed to lie in abutting coplanar relationship in sealed condition of the carton. Top flaps 24 and 25 are 30 connected to the panels 11 and 13, respectively, and are designed to lie in superimposed relation upon the opposed flaps 22 and 23.

35 Bottom closing flaps 26 and 27 are connected to the panels 10 and 12, respectively, along the fold line 21 and are designed to fold in abutting coplanar relationship. Bottom closing flaps 28 and 30 are connected to the panels 11 and 13, respectively, along the fold line 21 to underlie the panels 26 and 27 and to be secured thereto.

40 In order to reinforce the panel 12 opposite the double panel formed by adhering panels 10 and 17, I provide an auxiliary panel 31 which is adhered to the inner surface of the panel 12. This auxiliary reinforcing panel 31 thus reinforces 45 one side of the box while the panels 10 and 24 reinforce the other side of the box. As a result

the carton is possessed of considerable stacking weight while at the same time the closing flaps are of sufficiently light board to form an effective seal.

I have found that by reinforcing the opposed side walls in the manner disclosed the carton can withstand a considerable amount of compression. Much the same effect can be obtained by increasing the thickness of stock of which the carton is formed. However, in the latter instance, a greater weight of carton stock is usually required than in the present structure and at the same time the effectiveness of the end seal of the carton is substantially reduced.

It may be found for example that in order to possess the necessary stacking strength a carton must be formed of 28 point stock, or stock .028 inch in thickness. It may also be found that by reinforcing the two end walls of the carton in the manner specified, a structure having the same compressive strength may be obtained by using 16 point board or board .016 inch in thickness. As a certain amount of overlap is usually required to secure the carton walls in tubular formation, the reinforcing of the carton in the manner specified adds but little to the total amount of paper board used, as the double thickness areas are small relative to the entire area of the carton. Effective results may therefore be obtained without greatly increasing the amount of paperboard used. Furthermore, the upper and lower ends of the carton seal effectively, as they are formed of relatively light stock.

In Figures 5 and 6 of the drawings I disclose a modified type of carton B which has many of the features of the carton A and has certain advantages thereover. The carton B comprises a side wall panel 32, rear wall panel 33, side wall panel 34, and front wall panel 35 connected along parallel fold lines 36, 37, and 39. A reinforcing wall panel 40 is connected to the panel 35 along a fold line 41 parallel to the previously described fold lines.

A pair of fold lines 42 and 43 intersect the previously described fold lines at right angles to form the upper and lower edges of the container in its sealed form. Closing flaps 44 and 45 are connected to the panels 32 and 34 respectively along the fold line 42. These closing flaps are designed to extend into coplanar relation in closed form of the carton. Closure flaps 46 and 47 connected along the fold line 42 to the panels 33 and 35, respectively, are designed to overlie the panels 44 and 45 and be secured thereto. An auxiliary panel 49 is connected along the fold line 42 to the upper extremity of the auxiliary panel 40 for an object which will be later described in detail.

Closing flaps 50 and 51 are foldably connected along the fold line 43 to the panels 32 and 34, respectively. Closing flaps 50 and 51 are designed to fold into coplanar relationship in sealed form of the carton. A panel 52 is foldably connected along the fold line 43 to the panel 33 and a similar closing flap 53 is connected along the same line to the opposed panel 35. An auxiliary closing flap 54 is connected to the lower edge of the auxiliary panel 40 along the fold line 43.

A reinforcing panel 55 is secured to the panel 34 and is fastened to the inner surface thereof. An auxiliary panel 56 is foldably connected to the

panel 55 along fold line 57. An auxiliary flap 59 is secured to the panel 55 along the fold line 60. The fold line 57 substantially coincides with the fold line 42 when the panel 55 is in place, and similarly the fold line 60 substantially coincides with the fold line 43 in adhered position of the reinforcing panel.

The reinforcing flaps 56 and 59 are adhered to the inner surfaces of the closing flaps 45 and 51. Similarly when the carton blank is folded the panel 40 is adhered to the inner surface of the panel 32 and the auxiliary flaps 49 and 54 are secured to the closing flaps 44 and 50, respectively. Because of the double thickness of the side walls of the carton, and because of the double thickness of the auxiliary flaps connected to the reinforcing panels, the top closure flaps 44 and 45 and the bottom closure flaps 50 and 51 are resistant to folding and tend to remain in coplanar relationship with the panels from which they issue. This resistance to folding of the double thickness portions of the closing flaps forms a firm support beneath the overlying or underlying closure flaps to effect a good seal. In other words, inward pressure may be exerted against the outermost closing flaps without danger of folding the reinforced closing flaps inwardly due to the double thickness formation thereof. A better closing seal is often thus provided.

In accordance with the patent statutes, I have described the principles of construction and operation of my reinforced carton, and while I have endeavored to set forth the best embodiments thereof, I desire to have it understood that obvious changes may be made within the scope of the following claim without departing from the spirit of my invention.

I claim:

A carton comprising a series of panels foldably connected together, the end panels of the series being arranged in overlapping relation and adhered together to form a double thickness panel, end flaps on said panels at at least one end thereof including end flaps on both of said overlapped panels, said end flaps on said overlapped panels being adhered together, an auxiliary reinforcing panel underlying a second panel of said series, said reinforcing panel acting to reinforce said second panel, and end flaps on said reinforced panel underlying and adhered to the end flaps issuing from said second panel, the remaining panels being of single thickness.

REYNOLDS GUYER.
